UNITED STATES PATENT OFFICE.

ROBERT L. ELLERY, OF PORTSMOUTH, NEW HAMPSHIRE

ROLLER-BEARING.

SPECIFICATION forming part of Letters Patent No. 724,090, dated March 31, 1903.

Application filed June 7, 1902. Serial No. 110,607. (No model.)

To all whom it may concern:

Be it known that I, ROBERT L. ELLERY, a citizen of the United States, residing at Portsmouth, in the county of Rockingham and State of New Hampshire, have invented new and useful Improvements in Roller-Bearings, of which the following is a specification.

The object of this invention is to provide a cheap, simple, and durable antifriction side bearing for car-trucks, the same being particularly adapted to car-trucks which are pivotally attached to the body of the car.

The invention consists, in an antifriction side bearing for car-trucks, of a series of conical journalless rollers, their axial centers being located in the same plane and radial to the arc of a circle, in combination with a slotted spacing-frame adapted to receive said conical rollers and keep them apart.

The invention again consists in the instrumentalities hereinbefore set forth, in combination with means to hold said spacing-frame in the same plane as that in which the axial centers of the rollers are located.

The invention again consists in a base-plate provided with a guideway having curved side walls, a series of conical journalless rollers movable in said guideway, the axes of said rollers located in the same plane and radial to the arc of a circle, in combination with a slotted spacing-frame adapted to receive the conical rollers and keep them apart, said spacing-frame resting upon the side walls of the base-plate and being thus held in a plane passing through the axial centers of the rollers.

The invention again consists in the instrumentalities hereinbefore set forth, in combination with a top plate adapted to be fastened to the car-body and resting upon said rollers.

The invention finally consists in certain details of construction hereinafter particularly described, and set forth in the claims.

Referring to the drawings, Figure 1 is a plan view of a base-plate adapted to be fastened to the truck of the car constructed in accordance with my invention. Fig. 2 is a vertical section taken on line 2 2 of Fig. 1. Fig. 3 is a detail plan view of the spacing-frame with the rollers in position therein. Fig. 4 is a section taken on line 4 4 of Fig. 3. Fig. 5 is a detail plan view of the top plate. Fig. 6 is a transverse section taken on line 6 6

of Fig. 5 looking toward the right in said figure. Fig. 7 is a longitudinal central section taken through the parts illustrated in Figs. 1 55 to 6, inclusive, said parts being assembled in accordance with my invention. Fig. 8 is a transverse section of the parts shown in Fig. 7, taken on line 7 7 of Fig. 7.

Like numerals refer to like parts throughout the several views of the drawings.

In the drawings, 10 is a base-plate provided with holes 11, through which bolts may be inserted to fasten said base-plate to the truck of a car. The top of the base-plate 10 is provided with a curved guideway 12, having side walls 13 14 formed upon curves whose axial centers are coincident with the pivotal center of a car-truck and having end walls 15 15 radial to said side walls 13 and 14. Opening 65 out of the bottom of the curved guideway 12 are dust-pockets 16 16 to receive the dust which may enter the guideway 12 and prevent the same from interfering with the operation of the conical rollers hereinafter described. 70

The conical rollers 17 rest upon the base-plate 10 in the curved guideway 12. These rollers in operation rotate with their peripheries bearing upon the base-plate 10 in the guideway 12 and have their axial centers all 80 located in the same horizontal plane. The peripheries of said rollers converge toward a common point, said point being the pivotal center of the truck and the center about which the curved side walls 13 and 14 are described. The rollers 17 are kept apart by a spacing-frame 18, provided with slots 9 to receive said rollers. The spacing-frame 18 rests upon the curved side walls 13 and 14 and is thus held in the same horizontal plane as the 85 axial centers of said rollers, said spacing-frame being provided with radial walls 19, lying between the rollers 17.

At each end of the spacing-frame 18 are provided radial end flanges 20 20, which extend upwardly from said base-plate toward and almost into contact with the under side of a top plate 21. The top plate 21 is provided with holes 22, through which screws or bolts may be passed to secure said top plate 100 to the body of a car. Said top plate rests upon the rollers 17 and has curved side walls 23 24 projecting downwardly therefrom adjacent to and outside the base-plate side walls

13 and 14. The side walls 23 and 24 are formed upon the arcs of circles whose centers are the pivotal center of the truck to which the device is attached, the inner faces of said walls 23 and 24 forming guides for the spacing-frame 18 to guard against lateral displacement of said spacing-frame.

At each end of the base-plate 10 is fastened a dust-pad 25, preferably of felt, and extending upwardly from said base-plate to contact with the under side of the top plate 21. While said dust-pads may be rigidly fastened to the base-plate 10, as shown at the left of Fig. 7, I prefer to support the same upon a spring 26, as shown at the right of Fig. 7, said spring being fastened to the base-plate 10, and thus yielding to any inequalities upon the under surface of the top plate 21, and also as said pads wear the springs will force them upwardly to compensate for said wear, always keeping the upper surface of the pad against the under surface of the top plate 21 and preventing the dust from entering at the ends of said base-plate and top plate and getting into the curved guideway 12 and among the rollers 17.

The operation of my improved roller-bearing is as follows: The base-plate being fast to the truck, the top plate being fast to the car-body, and the rollers free to roll along the guideway 12 and between said base-plate and top plate, said rollers being kept apart by the spacing-frame 18, it is evident that as the truck turns upon its pivot with relation to the car-body, or vice versa, the plates 21 and 10 will move longitudinally with relation to each other and the rollers 17 and spacing-frame 18 will move between said plates in a manner well known to those skilled in the art, and as the rollers 17 move upon the base-plate 10, said rollers being conical in form and converging toward the pivotal center of the truck, it is evident that they will roll without sliding or grinding between the two plates, thus reducing the friction from a sliding friction to a theoretically perfect or rolling friction.

It will be seen that my improved roller-bearing for car-trucks is very cheap, strong, and durable in its construction and reduces the friction between the car-truck and car-body to a minimum and is provided with devices whereby the danger of dust and dirt collecting in the guideways or upon the bearing-surface of the plates, thus interfering with the action of the rollers, is reduced to a minimum.

The object of the upwardly-extended radial end flanges 20 upon the spacing-frame 18 is to prevent said frame from tipping upwardly away from its normal position, it being evident that said flanges will contact with the under side of the top plate 21 and prevent the spacing-frame from becoming displaced by tipping upward longitudinally thereof.

Having thus described my invention, what

I claim, and desire by Letters Patent to secure, is—

1. In an antifriction side bearing for car-trucks, a base-plate provided with a guideway having curved side walls, a series of conical journalless rollers movable in said guideway, the axes of said rollers located in the same plane and radial to the arc of a circle, and a slotted spacing-frame adapted to receive said conical rollers and keep them apart, said spacing-frame resting upon and extending laterally entirely across the top of said side walls and held by said side walls in said plane. 80

2. In an antifriction side bearing for car-trucks, a base-plate provided with a guideway having curved side walls, a series of conical journalless rollers movable in said guideway, the axes of said rollers located in the same plane and radial to the arc of a circle, a slotted spacing-frame adapted to receive said conical rollers and keep them apart, said spacing-frame resting upon and extending laterally entirely across the top of said side walls 90 and held by said side walls in said plane, and a top plate adapted to be fastened to a car-body, resting upon said rollers.

3. In an antifriction side bearing for car-trucks, a base-plate adapted to be fastened to a car-truck, provided with a guideway having curved side walls, a series of conical journalless rollers movable in said guideway, the axes of said rollers located in the same plane and radial to the arc of a circle; a top plate adapted to be fastened to a car-body, resting upon said rollers, and a slotted spacing-frame adapted to receive said rollers and keep them apart, said spacing-frame resting upon said side walls and provided with radial end flanges extending upwardly toward said top plate for the purpose specified. 105

4. In an antifriction side bearing for car-trucks, a base-plate provided with a guideway having curved side walls, a series of conical journalless rollers movable in said guideway, the axes of said rollers located in the same plane and radial to the arc of a circle, a slotted spacing-frame adapted to receive said conical rollers and keep them apart, said spacing-frame resting upon and extending laterally entirely across the top of said side walls and held by said side walls in said plane, and a top plate adapted to be fastened to a car-body resting upon said rollers and having curved side walls extending downwardly therefrom adjacent to and outside of said base-plate side walls, and forming guides for said spacing-frame to guard against lateral displacement thereof. 115

5. In an antifriction side bearing for car-trucks, a base-plate provided with a guideway having curved side walls, a series of conical journalless rollers movable in said guideway, the axes of said rollers located in the same plane and radial to the arc of a circle, a slotted spacing-frame adapted to receive said conical rollers and keep them apart, said spacing-frame resting upon said side walls and

held thereby in said plane, a top plate adapted to be fastened to a car-body resting upon said rollers and having curved side walls extending downwardly therefrom adjacent to 5 and outside of said base-plate side walls, and dust-pads fast to said base-plate and projecting upwardly therefrom to contact with the under side of said top plate.

6. In an antifriction side bearing for car-trucks, a base-plate provided with a guideway having curved side walls, a series of conical journalless rollers movable in said guideway, the axes of said rollers located in the same plane and radial to the arc of a circle, a slotted spacing-frame adapted to receive said conical rollers and keep them apart, said spacing-frame resting upon said side walls and held thereby in said plane, a top plate adapted to be fastened to a car-body resting upon 10 said rollers and having curved side walls extending downwardly therefrom adjacent to and outside of said base-plate side walls, and

dust-pads spring-supported upon said base-plate and projecting upwardly therefrom to contact with the under side of said top plate. 25

7. In an antifriction side bearing for car-trucks, a base-plate provided with a guideway having curved side walls and dust-pockets opening downwardly from said guideway, a series of conical journalless rollers movable 30 in said guideway, the axes of said rollers located in the same plane and radial to the arc of a circle, and a slotted spacing-frame adapted to receive said conical rollers and keep them apart, said spacing-frame resting upon 35 said side walls and held thereby in said plane.

In testimony whereof I have hereunto set my hand in presence of two subscribing witnesses.

ROBERT L. ELLERY.
